[57] CLAIM

The ornamental design for a duct canister for carrying and storing sections of a flexible duct used with portable ventilators as shown and described.

DESCRIPTION

FIG. 1 is a front and right side perspective view of a duct canister for carrying and storing sections of a flexible duct used with portable ventilators, showing my new design;

FIG. 2 is a left side elevational view thereof;

FIG. 3 is a front elevational view thereof;

FIG. 4 is a rear elevational view thereof;

FIG. 5 is a top plan view thereof; and,

FIG. 6 is a bottom plan view thereof.

The fragmentary criss-cross pattern shown on the front strip in FIGS. 1, 2, and 3, is shown partially for ease of illustration, and is understood to extend throughout the strip.

FIG. 1

FIG. 2

FIG. 4

FIG. 3

FIG. 5

FIG. 6
